FEELER-MOTION FOR LOOMS.

1,292,057.

Specification of Letters Patent. Patented Jan. 21, 1919.

Application filed September 11, 1918. Serial No. 119,413.

To all whom it may concern:

Be it known that I, ALONZO E. RHOADES, a citizen of the United States, residing at Hopedale, county of Worcester, and State 5 of Massachusetts, have invented an Improvement in Feeler-Motions for Looms, of which the following description, in connection with the accompanying drawings, is a specification, like characters on the drawings representing like parts.

This invention relates to feeler motions for filling replenishing looms, wherein a fresh supply of filling is furnished prior to the complete exhaustion of that in the 15 running shuttle.

The amount of filling remaining on the filling carrier or bobbin when it is ejected from the loom should be as small as possible consistent with proper weaving conditions and the formation of full picks. This amount will depend directly upon the feeler motion which should detect the approaching exhaustion of filling and initiate replenishment only when the desired degree 25 of exhaustion has been reached. In some types of feeler motions, the feeler member contacts with and is held from movement longitudinally of the shuttle so long as a working supply of filling is present, 30 but is displaced longitudinally of the shuttle when the filling supply is substantially exhausted. Many disturbing factors present themselves in the use of such feeler motions which tend to destroy their accuracy and reliability. It may happen at 35 times that the filling opposite the feeler may lay bare the bobbin and call for replenishment, when there yet remains sufficient filling to one side of the feeler contacting position to continue the weaving 40 operation for a number of additional picks, and owing to the delicacy of the feeler action it sometimes happens that the feeler will call a change when there yet remains in 45 the shuttle a working supply.

An important feature of the present invention therefore, consists in a plurality of feeler members movable longitudinally of the shuttle and held from such movement 50 by engagement with the filling until the filling is substantially exhausted on a detecting beat, each of said feelers acting upon different portions of the filling and its carrier within the shuttle. In order that the

feeler members, of which there are preferably two, may not call for change when a full or working supply of filling is present in the shuttle the present invention provides means for holding or locking the feeler members from movement longitudinally of the shuttle until just prior to substantial exhaustion of the filling, whereupon the holding means becomes ineffective and the feeler members are freed to the control of the filling and its carrier.

Another important feature of the present invention consists in causing the movement of the feeler members in opposite directions longitudinally of the shuttle to position an actuator and initiate filling replenishment 70 as the lay beats up.

Another important feature of the present invention consists in mounting the feeler members so that when the filling is substantially exhausted on a detecting beat, 75 the direction of movement of the feeler members will be one of separation, thereby obviating any bunching or pushing together of the nearly-depleted yarn mass upon the carrier, which might in some cases prevent 80 the delicate operation desirable in a feeler motion.

Other features of the invention will hereinafter be described in addition to those noted and then the several features will be 85 defined by the claims.

In the drawings:

Figure 1 is a perspective view of a feeler motion detached from the loom and showing a good practical form of the invention.

Fig. 2 is a plan view of the rear portion of the feeler motion, parts being broken away to show others beyond.

Fig. 3 is a perspective view of a portion 95 of the feeler motion and a shuttle into which the feeler members enter through the usual slots in the shuttle-box and side of the shuttle to detect the condition of the filling.

Fig. 4 is a view similar to that of Fig. 100 3, showing the two feeler members moved in opposite directions longitudinally of the shuttle by the forward push of the bobbin when the filling is substantially exhausted.

In illustrating and describing the present 105 invention it has been deemed unnecessary to discuss those known features of loom construction with which feelers are associ-

ated to perform their detecting function. It is usual in this type of feeler motion to provide the front wall of the shuttle-box as well as the front wall of the shuttle with 5 a slot through which the feeler may enter as the lay makes a detecting beat, but as these features are well understood by those skilled in the art, the present illustration and description will be confined more essentially to the construction and action of 10 the feeler motion itself.

The feeler supporting means or stand may be of any desired or preferred construction and as shown comprises the base 15 portion 1, on which is secured the cap piece 2 by suitable means such as screws 3 and which in connection with opposing cap piece 4 constitutes a guideway for a carrier or slide 5. The carrier in the present 20 instance of the invention is shown as having a reciprocating movement in the stand and normally held in rear position by means of spring 6, but as will be clearly obvious to those skilled in the art the carrier 5 25 may be of any other desired type, its essential in this respect being to provide a support for the feeler members which is normally held in rear position and is movable toward and from the front of the loom. 30 Mounted on the carrier 5, regardless of its particular construction are the two feeler members 6 and 7 which are characterized as having opposite movements longitudinally of the shuttle when the filling is substantially exhausted on a detecting beat. 35 In the present instance of the invention the feeler members are pivotally mounted at 8 and 9 respectively on the carrier 5 and are angularly formed to provide engaging end 40 portions 10 and 11, offset from their respective pivotal mountings on the carrier, the construction being such that should the feeler members 6 and 7 be pushed forwardly, or to the right, Fig. 1, by a substantially exhausted filling carrier or bobbin 45 on a detecting beat of the lay, the feeler members will be moved in opposite directions longitudinally of the shuttle.

Each of the feeler members 6 and 7 has 50 a frontwardly projecting portion 12 adapted to be engaged by the bifurcated end of a holder or slide 13 connected to the feeler carrier. Extending upwardly from the holder 13 is a lug 14 into which is threaded 55 the rod 15, a set nut 16 being preferably employed to hold the rod 15 and lug 14 in their adjusted relation. In order that the rod 15 may be better guided in its movement longitudinally as will hereinafter appear it 60 also passes through suitable bearings in the projecting lugs 17 and 18 which may be secured to the carrier 5. A spring 19 has one end seated against the face of the lug 17 and its other end bearing against the 65 shoulder 20 or other suitable abutment con-

nected to the rod 15, the construction being such that the spring 19 normally acts to move the rod 15 and its connected holder 13 rearwardly or toward the lay.

The rod 15 is preferably provided with a 70 blunt contacting end portion 21 which, at times, is adapted to engage a part movable with the lay when it makes its detecting beat, as will presently more fully appear.

The front end portion 12 of the feeler 75 members 6 and 7 act as a stop for the rearward movement of the holder 13 under the action of the spring 19, and the front end portions of the feeler members 6 and 7 are oppositely inclined or beveled as at 22, 80 a substantially straight holding portion 23 being adapted for engagement between the corresponding straight portions 24 of the bifurcated end of the holder 13, the construction being such that when the holder 85 13 is moved rearwardly into position indicated by Figs. 1, 2 and 3 the bifurcated end portion thereof embraces the front end portions of the feeler members 6 and 7 and prevents movement of the feeler members 90 in opposite directions longitudinally of the shuttle. This is the condition and relation of parts during normal weaving operations when a full working supply of filling is in the shuttle, substantially as indicated in 95 Fig. 3.

When the filling becomes exhausted to a predetermined extent and prior to substantial exhaustion, the end 21 of the rod 15 will be met by the front wall 25 of the 100 shuttle 26 or other part movable with the lay when the lay makes its detecting beat, as indicated in Fig. 4, and the holder 13 will be moved frontwardly sufficient to enable the inclined or beveled front edges 22 of the feeler members 6 and 7 to engage the oppositely inclined or beveled portions 27 of the bifurcated legs of the holder 13, the construction being such that when the holder 13 is thus moved by the rod 15 contacting with the shuttle or other part carried by the lay, should a working supply of filling still be present in the shuttle, the engaging end portions 10 and 11 of the feeler members 6 and 7 will sink into the filling 110 mass and prevent movement of the feeler members longitudinally of the shuttle, even though at such times the holder or lock 13 has been moved from its full locking position. Should the filling be substantially exhausted at such times, however, the end portions 10 and 11 of the feeler members 6 and 7 will contact with the surface of the filling carrier or bobbin 28, as indicated 115 in Fig. 4, as the lay makes its detecting beat, and will no longer be held from movement in opposite directions longitudinally of the shuttle by the forward push of the carrier or bobbin against the feeler members, and said feeler members will thus be 120 125 130

5 moved. As they are thus moved in opposite directions longitudinally of the shuttle the inclined edges 22 at the front end portion of the feeler members 6 and 7 will engage the oppositely inclined or beveled ends 27 of the holder 13 and will move said holder 13 frontwardly by their separating action under the forward push of the bobbin or filling carrier in the shuttle.

10 The movement of the feeler members 6 and 7 in opposite directions longitudinally of the shuttle due to the forward push of the filling carrier or bobbin against the feeling members when the filling is substantially 15 exhausted is utilized in the present invention to position a part for initiating filling replenishment, as will now be explained.

Pivotedly mounted upon the carrier 5 at 20 29 is an actuator 30 having a fan-tailed end 31, which when the actuator 30 is swung to the right, Fig. 3, into the position indicated in Fig. 4 is adapted to engage a finger 32 extending from the controller 33 connected to parts through which filling replenishment 25 is effected as will be understood by those skilled in the art. The connections between the controller 33 and the replenishing mechanism form no part of the present invention and being well understood by those familiar 30 with loom construction such connections are not further described.

The actuator 30 is normally under the action of a light spring 34 which maintains the actuator in the position indicated in Fig. 35 3 with the side of the actuator in contact with base portion of the lug 17. Extending laterally from the actuator 30 is an arm or projection 35, which is extended into the path of movement of the holder 13 as the latter is moved frontwardly by the opposite movement of the feeler members 6 and 7, as hereinbefore described, the construction being such that when the filling in the shuttle has become used up to a point sufficient to 45 permit the end 21 of the rod 15 to engage the shuttle wall or other part as the lay beats up, the holder 13 will be moved frontwardly preferably into contact with the arm or projection 35 but will not move sufficiently 50 far frontwardly to turn the actuator 30 into operative position. At this time the feeler members are unlocked and if a sufficient amount of filling remains in the shuttle to continue the weaving operation the mass of 55 filling will prevent movement of the feeler members 6 and 7 in opposite directions longitudinally of the shuttle as the lay makes its detecting beat, and the tail 31 of the actuator will remain in inoperative position 60 with respect to the finger 32 of the controller, but when the filling reaches substantial exhaustion, as indicated in Fig. 4, the feeler members 6 and 7 will be forced in opposite directions by the forward push 65 against the filling engaging ends of the

feeler members, and such separating action of the feeler members 6 and 7 will cause the inclined end portions 22 thereof to act upon the inclines 27 of the holder to further push the holder 13 frontwardly and perforce 70 cause the actuator 30 to move into operative position with respect to the finger 32 of the controller substantially as indicated in Fig. 4, so that on further frontward movement of the lay the carrier 5 to which parts are 75 connected will be moved frontwardly to cause the actuator to operate the controller and initiate filling replenishment.

It will be noted that the filling engaging ends of the feeler members act upon the filling or carrier at different points longitudinally thereof, so that should there be sufficient filling engaged by either of the feeler members to prevent its movement longitudinally of the shuttle as the lay beats up, the 80 feeler will not initiate filling replenishment. By movement of the feeler members longitudinally of the shuttle in opposite directions, it will be noted that the presence of a working supply of filling at either side of 85 the contacting point of the feeler members, will interrupt their movement in opposite directions longitudinally of the shuttle, until the working supply has become sufficiently depleted to no longer effectively act upon 90 and prevent movement of the feeler members.

When the parts are in normal position as indicated in Fig. 1 the front or tail portion 31 of the actuator is engaged with the lug 100 36 secured to the feeler stand, but when the carrier 5 is moved frontwardly under the action of the advancing lay the end of the actuator becomes freed from the lug 36 as indicated in Fig. 3. Should the actuator 105 have been moved into operative position, Fig. 4 by the frontward movement of the holder 13, as already described, and in consequence filling replenishment have been effected, it is desirable to return the feeler 110 members to their initial position as well as also the holder 13 into locking relation therewith as the lay moves back after replenishment. The spring 19 on the rod 15 may not always be sufficient for this purpose, therefore the lug 36 is provided with an inclined portion 37 adapted to engage a reversely inclined portion 38 on the front or tail end of the actuator 30 as the carrier 5 moves to initial position on the backward 120 movement of the lay. As the inclines 37 and 38 coact under the conditions described the actuator 30 will be positively thrown from the position in Fig. 4 to that of Fig. 1, and the projection 35 from the actuator will 125 move the holder 13 into locking engagement with the front end portions of the feeler fingers.

In the present embodiment of the invention the feeler fingers 6 and 7 have overlap 130

ping filling engaging portions as indicated and the movement of the feeler members by the forward push against them when the filling is substantially exhausted is in a 5 separated direction but evidently this directional movement of the feelers may be readily changed without departing from the true spirit of the invention.

Claims:

- 10 1. In a feeler motion for looms, the combination of a feeler slide, a plurality of feeler members movable longitudinally of the shuttle by frontward pressure and held from such movement by engagement with the filling until the filling is substantially exhausted, a lock for holding the feeler members from movement longitudinally of the shuttle, and means effective before the filling reaches substantial exhaustion to unlock the plurality of feeler members and free them to the control of the filling.
- 15 2. In a feeler motion for looms, the combination of a feeler carrier movable toward and from the front of the loom, two feeler members mounted on said carrier for movement longitudinally of the shuttle and held from such movement on a detecting beat by engagement with the filling until the filling is substantially exhausted, a lock to prevent movement of the two feeler members longitudinally of the shuttle, and means rendered effective before the filling reaches substantial exhaustion to unlock the feeler members.
- 20 3. In a feeler motion for looms, the combination of a carrier movable toward and from the front of the loom, two feeler members mounted on the carrier and movable in opposite directions by the frontward push upon the feeler members when the filling is substantially exhausted on a detecting beat, a lock to prevent movement of the two feeler members in opposite directions longitudinally of the shuttle, and means rendered effective before the filling reaches substantial exhaustion to unlock the feeler members.
- 25 4. In a feeler motion for looms, the combination of a carrier, two feeler members mounted on the carrier and movable, the one toward one end of the shuttle and the other toward the opposite end of the shuttle, by the frontward push upon the feeler members when the filling is substantially exhausted on a detecting beat, and means controlled by the feeler members for initiating filling replenishment.
- 30 5. In a feeler motion for looms, the combination of a carrier, two feeler members mounted thereon for movement in opposite directions longitudinally of the shuttle by the frontward push against said members when the filling is substantially exhausted and an actuator positioned by opposite movement of the two feeler members on a detecting beat to initiate replenishment of filling.
- 35 6. In a feeler motion for looms, the com-

bination of a carrier, two feeler members mounted thereon for movement in opposite directions longitudinally of the shuttle by the frontward push against said members when the filling is substantially exhausted, a lock 70 to prevent movement of the feeler members in opposite directions and rendered ineffective before the filling reaches substantial exhaustion and an actuator positioned by opposite movement of the two feeler members on a detecting beat to initiate filling replenishment.

7. In a feeler motion for looms, the combination of a carrier, two feeler members connected to the carrier for movement in opposite directions by the frontward push upon said members when the filling is substantially exhausted on a detecting beat, a lock for preventing movement of the said members in opposite directions until the filling 85 has approached within a predetermined degree of exhaustion and then rendered ineffective, and filling engaging portions on said members to prevent movement of the members in opposite directions after they have 90 been released from the lock when a working supply of filling is present in the shuttle.

8. In a feeler motion for looms, the combination of a carrier normally held in rearward position, two feeler members connected to the carrier for movement in opposite directions by the frontward push upon said members, when the filling is substantially exhausted, means for holding the feeler members from such opposite movement until the filling has reached a predetermined amount prior to substantial exhaustion and then freeing the members to such opposite movement, and means carried by the feeler members to engage the filling 100 and prevent movement of the members in opposite directions when a working supply of filling is present after said members are freed from said holding means.

9. In a feeler motion for looms, the combination of a carrier normally held in rearward position, two feeler members connected to the carrier for movement in opposite directions by the frontward push upon said members, when the filling is substantially 115 exhausted, means for holding the feeler members from such opposite movement until the filling has reached a predetermined amount prior to substantial exhaustion and then freeing the members to such opposite movement, and means carried by the feeler members to engage the filling and prevent movement of the members in opposite direction when a working supply of filling is present after said members are freed from 120 said holding means, and an actuator positioned by movement of the feeler members in opposite directions on a detecting beat to initiate filling replenishment.

10. In a feeler motion for looms, the com- 125

bination of two feeler members mounted for movement in opposite directions by the forward push against said members when the filling is substantially exhausted on a detecting beat, and provided with filling engaging portions to engage the filling at different points longitudinally of the filling carrier, and means for initiating filling replenishment when said two members have been moved in opposite directions on a detecting beat.

11. In a feeler motion for looms, a carrier mounted for movement toward and from the front of the loom, two feeler members connected to the carrier for movement in opposite directions by the forward push against said members when the filling is substantially exhausted on a detecting beat, and provided with overlapping ends having filling engaging portions to engage the filling at different points longitudinally of the filling carrier, and means for initiating filling replenishment when said two members have been moved in opposite directions on a detecting beat.

12. In a filling replenishing loom, the combination of a carrier, two feeler members connected to the carrier for movement in opposite directions when the filling is substantially exhausted on a detecting beat, an actuator connected to the carrier, connections between the two feeler members and actuator to effect movement of the actuator into operative position by opposite movement of the feeler members as the lay beats up, and means operative by the actuator for initiating filling replenishment.

13. In a filling replenishing loom, the combination of a carrier, two feeler members connected to the carrier for movement in opposite directions when the filling is substantially exhausted on a detecting beat, means to hold the two feeler members from such movement until the filling has reached a predetermined amount and to then free them to such movement, an actuator connected to the carrier, connections between the two feeler members and actuator to effect movement of the actuator into operative position by opposite movement of the feeler members as the lay beats up, and means operative by the actuator for initiating filling replenishment.

14. A feeler motion for looms, comprising, in combination, a carrier movable toward and from the front of the loom, two feeler members pivotally mounted on the carrier and displaced longitudinally of the shuttle in opposite directions by the forward push against said members when the filling is substantially exhausted, an actuator movable with the carrier and also movable into operative position by the movement of the feeler members in opposite directions on a detecting beat, and a controller actuated by the

actuator when operatively positioned on a detecting beat of the lay for initiating filling replenishment.

15. A feeler motion for looms, comprising, in combination a carrier, two feeler members mounted on the carrier for movement in opposite directions when the filling is substantially exhausted on a detecting beat, a part for holding said members from movement in opposite directions, means for moving said part from holding position when the filling reaches a predetermined amount prior to substantial exhaustion, said members acting to give additional movement to said part by their movement in opposite directions, an actuator movable to operative position by the additional movement of said part, and means actuated by the actuator when in operative position as the lay beats up to initiate filling-replenishment.

16. In a feeler motion for looms, the combination of two feelers to feel for the filling in the shuttle and mounted for movement in opposite directions longitudinally of the shuttle when the filling is substantially exhausted on a detecting beat, and means for initiating replenishment of filling when the two feeler members are moved in opposite directions on a detecting beat.

17. A feeler motion for looms, comprising, in combination, two feeler members mounted for movement longitudinally of the shuttle in opposite directions and held from such movement by engagement with the filling until substantial exhaustion thereof, and means rendered effective for replenishing filling when the feeler members are moved longitudinally of the shuttle in opposite directions on a detecting beat.

18. In a feeler motion for looms, the combination of a carrier movable toward and from the front of the loom, two feeler members on the carrier relatively movable in opposite directions and held from such movement by engagement with the filling until substantial exhaustion thereof, a lock to prevent movement of the feeler members in opposite directions until the filling reaches a predetermined degree of exhaustion and then freeing the feeler members to the control of the filling, and means for initiating replenishment of filling when the feeler members are moved in opposite directions on a detecting beat.

19. In a feeler motion for looms, the combination of two feeler members mounted for movement in opposite directions longitudinally of the shuttle and held from such movement by engagement with the filling on a detecting beat until substantial exhaustion thereof, and an actuator positioned by movement of the feeler members in opposite directions to initiate filling replenishment.

20. A feeler motion for looms, comprising, in combination, two feeler members movable

in opposite directions longitudinally of the shuttle and provided with filling engaging portions to engage the filling at different points longitudinally of the filling carrier 5 on a detecting beat and prevent movement of the feeler members in opposite directions until substantial exhaustion of filling, and means for initiating filling replenishment when the feeler members have been moved 10 in opposite directions.

21. A feeler motion for looms, comprising, in combination, two feeler members movable in opposite directions longitudinally of the shuttle and provided with filling engaging portions to engage the filling at different points longitudinally of the filling carrier on a detecting beat and prevent movement of the feeler members in opposite directions until substantial exhaustion of filling, means 15 for locking the feeler members from movement in opposite directions until the filling has been depleted to a predetermined amount and then freeing the feeler members to the control of the filling, and means for initiating filling replenishment when the feeler members have been moved in opposite directions. 20

22. In a feeler motion for looms, the combination of a feeler carrier, two feeler members connected thereto for separating movement of the engaging ends thereof in a direction longitudinally of the shuttle by the forward push thereon when the filling is substantially exhausted on a detecting beat, 25 and a lock for holding the two feeler members from such separating movement and to free them to such movement prior to substantial exhaustion of filling that they may thereafter be controlled as to such movement 30 by the character of the surface engaged by the feeler members.

23. In a feeler motion for looms, the combination of two feeler members mounted for

separating movement in opposite directions longitudinally of the shuttle and held from such movement by engagement with the filling until the filling is substantially exhausted, a lock to prevent separating movement of the feeler members in opposite directions and rendered ineffective before the filling reaches substantial exhaustion, and an actuator positioned by the separating movement of the two feeler members on a detecting beat to initiate replenishment of filling. 45

24. In a feeler motion for looms, the combination of two feeler members mounted for separating movement in opposite directions when the filling is substantially exhausted on a detecting beat, a lock for preventing separating movement of the said members in opposite directions until the filling has approached within a predetermined degree of exhaustion and then rendered ineffective, and filling engaging portions on said members to prevent separating movement of the members in opposite directions after they have been released from the lock when a working supply of filling is present in the shuttle. 50

25. In a feeler motion for looms, the combination of two feeler members movable longitudinally of the shuttle in opposite directions on a detecting beat and held from such movement by engagement with the filling until substantial exhaustion thereof, an actuator adapted to be moved into operative position when the feeler members are moved longitudinally of the shuttle, and means for moving the actuator into inoperative position as the feeler members resume their feeling position after detection of substantial exhaustion of filling. 55

In testimony whereof, I have signed my name to this specification.

ALONZO E. RHOADES.
